[57] CLAIM

The ornamental design for a closure for a box for straws, as shown and described.

DESCRIPTION

FIG. 1 is a perspective view of closure for a box for straws showing our new design;

FIG. 2 is a top plan view thereof;

FIG. 3 is a front elevational view thereof;

FIG. 4 is a bottom plan view thereof;

FIG. 5 is a rear elevational view;

FIG. 6 is a side elevational view thereof, the opposite side being a mirror image thereof;

FIG. 7 is a cross-sectional view thereof taken along line VII—VII of FIG. 2; and,

FIG. 8 is a cross-sectional view thereof taken along line VIII—VIII of FIG. 2 thereof.

The broken line showing of box for straws is for illustrative purposes only and forms no part of the claimed design.
